UNITED STATES PATENT OFFICE

143,035

DESIGN FOR A GARDEN MARKER

Albert Rubenstein, Washington, D. C.

Application June 22, 1945, Serial No. 120,246

Term of patent 14 years

(Cl. D35—1)

To all whom it may concern:

Be it known that I, Albert Rubenstein, a citizen of the United States, residing at Washington, in the District of Columbia, have invented a new, original, and ornamental Design for a Garden Marker, of which the following is a specification, reference being had to the accompanying drawing, forming a part thereof.

Figure 1 is a side elevational view of a garden marker showing my new design, the other side thereof being of a like design; and

Figure 2 is an edge elevational view thereof.

I claim:

The ornamental design for a garden marker, as shown and described.

ALBERT RUBENSTEIN.
